UNITED STATES PATENT OFFICE.

JOSEPH L. CLEMENTS, OF BIRMINGHAM, ALABAMA.

DESIGN FOR A BROOM AND MOP HANGER.

60,980.

Specification for Design.

Patented May 23, 1922.

Application filed November 7, 1921. Serial No. 513,607. Term of patent 3½ years.

To all whom it may concern:

Be it known that I, JOSEPH L. CLEMENTS, a citizen of the United States, residing at Birmingham, in the county of Jefferson and State of Alabama, have invented a new, original, and ornamental Design for Broom and Mop Hangers, of which the following is a specification, reference being had to the accompanying drawing, forming part hereof.

The figure is a plan view of a mop and broom hanger showing my new design and omitting the screw eye by means of which it is suspended.

I claim:

The ornamental design for a broom and mop hanger substantially as shown.

JOSEPH L. CLEMENTS.
